PENCIL FERRULE

Albert L. Davis, Watertown, Conn., assignor to
The Waterbury Brass Goods Corporation,
Waterbury, Conn., a Corporation of Connecti-
cut

Application May 10, 1933. Serial No. 670,255

8 Claims. (Cl. 120—38)

This invention relates to new and useful improvements in eraser holders or attachments for pencils, and has for an object to provide an eraser attachment which may be manufactured at low cost, which may be easily applied to and removed from a pencil and therefore renewed, and which may be so proportioned as to provide an eraser of practically any size desired.

Other objects and advantages will become apparent from a consideration of the following detailed description taken in connection with the accompanying drawing wherein satisfactory embodiments of the invention are shown. However, it will be understood that the invention is not limited to the details disclosed but includes all such variations and modifications as fall within the spirit of the invention and the scope of the appended claims.

In the drawing:

Fig. 1 is a side elevational view showing the attachment of the invention in place on a pencil;

Fig. 2 is an enlarged longitudinal sectional view through the eraser receiving part of the attachment;

Fig. 3 is a bottom plan view of the part of Fig. 2;

Fig. 4 is an enlarged side elevational view of the eraser carrying part, the view being taken at right angles to Fig. 2 and a portion being broken away;

Fig. 5 is a view partly in elevation and partly in section and showing, on an enlarged scale, a cap-like pencil receiving part permanently secured to an end of a pencil;

Fig. 6 is a top plan view of Fig. 5, a portion being broken away;

Fig. 7 is an enlarged view partly in section and partly in elevation and illustrating the first step in assembling the eraser receiving or carrying part on the pencil receiving or carrying part;

Fig. 8 is a similar view but illustrating the relation of the parts at the completion of the operation of Fig. 7;

Fig. 9 is a similar view showing the parts completely assembled; and

Fig. 10 is an enlarged view partly in section and partly in elevation and showing a slightly modified construction of pencil receiving or pencil carried part.

Referring in detail to the drawing and at first more particularly to Figs. 1 through 8, the improved attachment is generally designated 15, and in Fig. 1 is shown as applied to any suitable pencil 16. The attachment comprising a two-

part ferrule including a cap-like pencil receiving part 17 and an eraser receiving part 18 removably secured to the cap or pencil receiving part as will later be more fully described. Part 17 as shown includes an end wall 19 and this part is of such diameter that it may be forced over the outer end of a pencil so as to tightly embrace said end and as here disclosed the part is permanently and immovably secured to the pencil. It is immovable on the pencil owing to the forced fit and it may additionally be secured to the pencil by pressing in by punches at spaced points as at 20.

The outer or upper end portion of part 17 has its outer peripheral surface 21 tapered or inclined whereby the outer end portion 22 is of considerable diameter and is followed by a portion of gradually decreasing diameter so that said outer or upper end portion is in the nature of a head having tapering or inclined side walls. A single lug 23 is carried by the enlarged outer end portion 22 and the lug extends laterally or radially with respect to the part and is formed by pressing out a portion of the material of the part as clearly shown in Figs. 5 and 6 although it will be apparent that the lug might be a separate piece secured in place in any suitable manner.

Eraser receiving part 18 is hollow, being tubular or cylindrical, and this part is preferably of greater diameter than part 17 and is formed with an outer open end and may have beads pressed or rolled into its side wall as shown at 24. An eraser 25 of a diameter to be snugly received in the part 18 may be fitted into said part and then further secured as by pressing or punching in portions of the part as at 26. This eraser it will be noted is of substantially greater diameter than the pencil and the eraser extends or projects through the open end of part 18 so as to be available for use. The large eraser provides a considerable area for use and the eraser may be of practically any desired size.

At its inner end part 18 includes an annular flange 27 and inwardly of said flange there is provided a wall 28. This flange 27 is formed by forcing the wall 25 inwardly of the part and the flange is therefore formed by folding of the metal upon itself so that the flange is of a double thickness of material. It will be appreciated that thin or light gauge material is used and that the wall thickness of the flange is not greater and that the double thickness of material greatly strengthens the flange. Attention is directed to the fact that the inner peripheral surface 29 of the flange is inclined or tapered, the arrangement being such that the flange is of greatest diameter immedi-

ately adjacent the wall 28 and of least diameter at its free or open end. At any desired point, flange 27 is provided with a notch 30 opening through its free or outer end and at a point in spaced relation to said notch 30 a recess 31 is formed in the flange this recess being in the form of a depression in or an opening through the inner layer of the material forming the flange.

It is preferred that both the parts 17 and 18 be formed of sheet brass or other resilient material and this is particularly true of the part 18 and the constructing of this part of such material provides a flange 27 which is somewhat yielding or resilient. The diameter of the free or entrance 10 end of the flange 27 is such with respect to the outer end portion 22 of part 17 that said end portion may be forced into the flange by slightly springing the flange. This assembly may be accomplished by disposing the flange partly over the 15 outer end portion 22 of the part 17 or by partially inserting said end portion in the flange at one side as shown in Fig. 7. The parts should be so positioned that lug 23 and notch 30 are in alignment and then on pressure being applied the 20 flange is sprung or forced over the head-like portion 22 so that the relative positions of the parts are as shown in Fig. 8.

Next, the parts are turned relatively whereby the notch 30 is carried away from the lug 23 or whereby said lug is carried away from the 30 notch, and as the lug engages the inner surface of the flange there is a cam-like action tending to draw the parts slightly into eccentric relationship whereby the inclined surface 21 of part 35 17 is forced into tight and overlapping relationship with the inner inclined surface 29 of the flange. This engagement takes place particularly at a point opposite the lug 23 as is best shown in Fig. 9. The parts may be turned relatively until the lug 23 snaps into the recess 31 when the parts will be locked together. Owing to the fact that the inclined surfaces 21 and 29 of the respective parts are forced into tight engagement by the camming action above referred 40 to, the parts will be rigidly connected and the eraser receiving part 18 will not wobble. Further, owing to the fact that the parts have been shifted into an eccentric relationship with the 45 inclined surface of one overlapping the inclined surface of the other, the parts are securely locked together so that they cannot be pulled apart.

The wall 28 may be formed with a slight bow or is formed slightly concavo-convex with the convex surface on the under or outer side. 50 Therefore, when the parts are telescoped as shown in Figs. 8 and 9 the wall 28 is slightly sprung upwardly by the pressing of the parts together. While the wall is thus sprung, the parts are turned relatively and then on the pressure being released the wall tends to return to normal condition due to its resiliency or spring action, and the parts having been moved into the slightly eccentric relation above mentioned, the overlapping inclined surfaces further tightly engage as the wall 28 attempts to force the part 55 17 out of the flange. This spring action of the wall also assists somewhat in maintaining the lug 23 in the recess 31.

With the present arrangement it will be noted that but one lug 23 is needed and in manufacture it is cheaper and easier to provide a pencil receiving part or part 17 with one such lug than it is to provide it with two lugs. This part is substantially permanently attached to the pencil 60 and when the part 18 is assembled on the part

17 there is no free relative movement of the parts. This is caused by the camming action and the spring action above referred to. Should the eraser 25 wear down so as to be no longer useful, part 18 may be easily removed by shifting it to bring the notch 30 in alignment with the lug 23 and a new part 18 equipped with a new eraser may be easily applied.

In Fig. 10 is shown a slight modification in which the end wall of the cap may be bowed or concavo-convex as indicated at 32 to have the same spring effect as the wall 28 in the eraser receiving member 18.

Having thus set forth the nature of my invention, what I claim is.

1. An article of manufacture including a two part ferrule comprising a pencil receiving part and an eraser receiving part, said eraser receiving part having an annular flange at its inner end, said pencil receiving part including a portion to telescope with said flange, and means whereby on relative rotation of said parts after they have been telescoped a surface of one is wedged against a complementary surface of the other and the parts are rigidly connected.

2. An article of manufacture including a two part ferrule comprising a pencil receiving part and an eraser receiving part, said eraser receiving part having an annular flange at its inner end, said pencil receiving part including a portion to telescope with said flange, said flange including an inclined peripheral surface, said portion of the pencil receiving part including a complementary inclined peripheral surface, and means whereby on relative rotation of said parts after they have been telescoped the said inclined surfaces are wedged against one another and the parts are rigidly connected.

3. An article of manufacture including a two part ferrule comprising a pencil receiving part and an eraser receiving part, said eraser receiving part having an annular flange at its inner end, said flange having a notch opening through its inner end, a laterally extending lug on the pencil receiving part, said pencil receiving part including a portion to telescope with said flange on aligning of said lug and notch, said flange including an inclined peripheral surface, said portion of the pencil including a complementary inclined peripheral surface, and said lug adapted to engage a surface of said flange and draw said inclined surfaces into engagement to secure the parts together on relative rotation of the parts after they have been telescoped.

4. An article of manufacture including a two part ferrule comprising a pencil receiving part and an eraser receiving part, said parts each having a free end portion of which one is complementary to the other, said end portion of one of said parts adapted to be sprung over the said end portion of the other part, and cooperating camming means whereby said parts are interlocked to rigidly secure them together on relative turning movement of the parts after said end portions have been sprung one over the other.

5. An article of manufacture including a two part ferrule comprising a pencil receiving part and an eraser receiving part, said eraser receiving part having an annular flange at its inner end, said flange having a notch opening through its inner end, said pencil receiving part in its outer end portion including a portion of increased diameter, a laterally extending lug on the outer end portion of the pencil receiving part, said pencil receiving part adapted to have its outer

end portion telescoped into the flange of the eraser receiving part on alignment of the lug with the notch in said flange, and said parts adapted thereafter to be turned relatively to space the lug and notch and cause the lug to engage the inner surface of the flange to draw the inner surface of the flange into engagement with the portion of increased diameter of the pencil receiving part whereby to rigidly secure the eraser receiving part to the pencil receiving part. 5

6. An article of manufacture including a two part ferrule comprising a cap forming pencil receiving part and an eraser receiving part, said eraser receiving part having an annular flange 10 at its inner end, said flange having its inner peripheral surface inclined whereby the flange is of least diameter adjacent its free end, said flange having a notch opening through its free end, said cap having the outer peripheral surface 15 of its outer end portion inclined whereby it includes a portion of greater diameter and a portion of gradually decreasing diameter inwardly of said portion of greater diameter, said cap having a laterally extending lug on its portion of greater 20 diameter, said flange of such diameter at its inner end that the portion of greater diameter of the cap may be forced therethrough on aligning the lug of the cap with the notch in the flange whereby to dispose the portion of greater diameter of 25 the cap within the flange to locate the inclined surface of one in opposing relation to the inclined surface of the other, and said parts adapted thereafter to be turned one on the other to space the lug and notch and cause the lug to bear against 30 a portion of the inner inclined surface of the flange and draw a portion of the inclined surface of the flange against a portion of the inclined surface of the cap and thereby secure the eraser receiving part to the cap. 35

7. An article of manufacture including a two part ferrule comprising a cap forming a pencil receiving part and an eraser receiving part, said eraser receiving part having an annular flange 40 at its inner end, said flange having its inner peripheral surface inclined whereby the flange is of least diameter adjacent its free end, said flange having a notch opening through its free end, said cap having the outer peripheral surface of its outer end portion inclined whereby it includes a portion of greater diameter and a portion of gradually decreasing diameter 45 inwardly of said portion of greater diameter, said cap having a laterally extending lug on its portion of greater diameter, said flange of such diameter at its inner end that the portion of greater diameter of the pencil receiving part may be forced therethrough on aligning the lug of the pencil receiving part with the notch in the flange whereby to dispose the portion of greater diameter of the pencil receiving part in the flange to locate the inclined surface 50 of one in opposing relation to the inclined surface of the other, said parts adapted thereafter to be turned one on the other to space the lug and notch and cause the lug to bear against a portion of the inner inclined surface of the flange and force a portion of the inclined surface of the flange against a portion of the inclined surface of the pencil receiving part whereby to dispose a section of the portion of greater diameter of the pencil receiving part over a section of the inclined surface of the flange, and said pencil receiving part adapted on entering the flange to engage and spring said bowed wall whereby on the parts being released after being turned relatively the spring wall will tend to return to normal position and will force the overlapping sections against one another to secure the parts together. 55
